George H. Heydt.
by *S. C. Munro, Atty.*

UNITED STATES PATENT OFFICE.

GEORGE H. HEYDT, OF NEW YORK, N. Y., ASSIGNOR TO WESTERN ELECTRIC COMPANY,
INCORPORATED, OF NEW YORK, N. Y., A CORPORATION OF NEW YORK.

AUTOMATIC SWITCH.

1,205,536.

Specification of Letters Patent. Patented Nov. 21, 1916.

Application filed June 10, 1916. Serial No. 102,893.

To all whom it may concern:

Be it known that I, GEORGE H. HEYDT, a citizen of the United States, residing at New York, in the county of New York and State 5 of New York, have invented certain new and useful Improvements in Automatic Switches, of which the following is a full, clear, concise, and exact description.

This invention relates to automatic 10 switches, and more particularly to switches in which a brush-carrying shaft is driven in a rotary direction, a brush set upon such shaft being arranged to successively engage the terminal sets in a contact bank.

15 The object of this invention is to provide an arrangement by which a rotatable brush is made to engage contacts arranged in a line in the plane of rotation of said brush, such line not being an arc of any circle 20 whose center is at the axis of rotation. To accomplish this result it is necessary that the brush be capable of variable motion radially. In a preferred form of the invention a brush is fixed to a slide carried by an arm secured 25 to a rotatable driving shaft, the slide being spring-pressed inwardly. The desired amount of outward radial motion is obtained by the action of a cam rotatably mounted on the driving shaft and driven 30 through an idler shaft by suitable gearing. The cam is so designed, and driven at such a speed that it forces out the slide to the extent required by the angular position of 35 said brush at that particular time.

35 In the embodiment shown, the invention is arranged for use in a telephone exchange system; but it is obviously capable of arrangement for other uses.

The general operation of the switch of the 40 present disclosure is as follows: A brush-carrying shaft is arranged to be driven in both a vertical and a rotary direction, the brushes on such shaft being arranged to engage terminal sets in a contact bank of the 45 well-known panel type. The brush shaft is arranged to be stepped, first vertically and then in a rotary direction, by means of stepping mechanism which it has not been considered necessary to describe, that shown in 50 Patent No. 815,176 of Keith, Erickson and Erickson, issued Mar. 13, 1906, being of a suitable nature for this purpose.

The invention will be better understood from the following detailed description,

reference being had to the accompanying 55 drawings.

In the drawings, Figure 1 is a plan view of a panel bank showing two switches in different positions relative to said bank; Fig. 2 is a front elevation of a contact bank and Fig. 3 shows the mechanism for operating the brushes and the arrangement of the terminals in the bank.

The contact bank is divided horizontally into two sections 1 and 2, the upper section 65 containing the multiples of the ring terminals of 100 lines, while the lower section contains the multiples of the tip terminals of the same 100 lines. Each switch has a separate brush for each section, the pair 3, 3' 70 constituting a set. The sections are further divided horizontally into ten groups, each group containing the multiple contacts of ten terminals, the contacts of each group being offset so as to lie in the same plane. 75

Only the structure of the switch-operating mechanism shown at the left will be described, since that of the structure shown at the right is identical. A rotatable shaft 4 carries fixedly secured to it arms 5 and 6. 80 Also fixed on shaft 4 is a gear wheel 7 which engages a pinion 8 secured to an idler shaft 9. A sleeve 10, rotatable on the shaft 4 and mounted thereon, carries cams 11 and 12 and a pinion 13 fixedly secured to it, the pinion 85 13 being arranged to be driven through a gear wheel 14 fixedly secured to the idler shaft 9.

Only the operation of the extending means for brush 3 will be described, since 90 that of the extending means for brush 3' is the same. A slide 15 is non-rotatably mounted on the arm 5 and is spring pressed inwardly by the action of a spring 16. The brush is fixed to this slide 15 and passes 95 through a guide aperture in an end piece 17, which also serves as a stop for the spring 16. An anti-friction roller 18 is carried by the slide 15 and engages cam 11.

The cam, as designed in the present case, 100 is arranged to rotate at three times the speed of the stepping shaft, this speed being obtained through suitable proportioning of gear wheels 7, 8, 14 and 13. This gear relation is required since the arm 5, in making 105 the ten steps necessary to engage the tenth contact, swings over an arc of ninety degrees. In order that the cam may again

be at its greatest radial length at this time, it will have to make three-quarters of a revolution.

Since the arc over which the brush travels on each step will vary with the radius of rotation, it is necessary that the individual contacts 25 of the group be placed at varying intervals. This spacing is shown in Fig. 1, in which the distance between successive contacts increases toward the ends of a group.

The shafts 4 and 9 are rotatably and slidably mounted in suitable bearings. A lifting yoke 19 maintains the gear wheels in engagement during upward movement of the stepping shaft 4. The shafts 4 and 9 are free to rotate in the yoke 19, and are held in fixed relation to one another by collars 20, 21 and 22, 23 on shafts 4 and 9 respectively.

Soldering terminals for the strips are shown at 24.

By a suitable arrangement of the terminal groups and a change in the shape of the contacting portion of the brush, the switch may be adapted for use in a system in which the rotary motion of the stepping shaft 4 takes place before the vertical motion. In an arrangement of this kind, stepping mechanism of the type disclosed in an application by O. F. Forsberg, Serial No. 6302, filed February 5, 1915, would be suitable for imparting motion to the brush shaft.

What is claimed is:—

35 1. In an automatic switch, a rotatable shaft, a brush carried thereby, and means for causing said brush to traverse, during rotation of said shaft, a series of contacts, said contacts being at various distances from the axis of the shaft.

2. In an automatic switch, a rotatable shaft, a radially movable brush carried thereby, and means for causing a constantly varying radial motion of the brush.

3. In an automatic switch, a rotatable 45 shaft, an arm mounted thereon, a brush carriage mounted on said arm, a brush, and means for causing said brush to traverse, during rotation of said shaft, a series of contacts, said contacts being arranged at 50 various distances from the axis of the shaft.

4. In an automatic switch, a rotatable shaft, an arm mounted thereon, a brush carriage mounted on said arm, a radially movable brush, and means for causing a constantly varying radial motion of the brush. 55

5. In an automatic switch, a rotatable shaft, a radially movable brush carried thereby, a series of contacts, said contacts being arranged at various distances from 60 the axis of said shaft, and means for causing said brush, during rotation in the plane of said contacts, to establish connection to any desired one of said contacts.

6. In an automatic switch, a rotatable 65 shaft, an arm mounted thereon, a brush movably carried on said arm, a series of contacts arranged at various distances from the axis of rotation of said shaft, and means for causing said brush to establish connection to 70 any desired one of said contacts.

7. In an automatic switch, a series of contacts arranged in a straight line, a brush rotatable in the plane of said contacts and arranged to establish connection to any desired one of said contacts. 75

In witness whereof I hereunto subscribe my name this 8th day of June, A. D. 1916.

GEORGE H. HEYDT.
